DESK SET SUPPORT

Morrison M. Davis, Houston, Tex.

Application October 12, 1950, Serial No. 12,532

Term of patent 7 years

(Cl. D74—1)

To all whom it may concern:

Be it known that I, Morrison M. Davis, a citizen of the United States, residing at Houston, in the county of Harris and State of Texas, have invented a new, original, and ornamental Design for Desk Set Support, of which the following is a specification, reference being had to the accompanying drawing, forming part thereof.

The figure is a perspective view of a desk set support, showing the essential features of my new design in full lines.

I claim:

The ornamental design for a desk set support, as shown and described.

MORRISON M. DAVIS,
